UNITED STATES PATENT OFFICE.

WILLIAM KERR EDGAR, OF LAWRENCE, KANSAS, ASSIGNOR TO THE EDGAR STEEL
SEAL & MFG. CO., OF LAWRENCE, KANSAS.

MILK-CAN SEAL.

1,415,431.

Specification of Letters Patent.

Patented May 9, 1922.

Application filed September 19, 1919. Serial No. 324,757.

To all whom it may concern:

Be it known that I, WILLIAM KERR EDGAR, a citizen of the United States, residing at Lawrence, in the county of Douglas and 5 State of Kansas, have invented a new and useful Milk-Can Seal, of which the following is a specification.

The present invention relates to seals particularly adapted to seal the lid of a receptacle such as a milk can and the primary object is to provide a seal which will become broken upon any attempt to remove the cover, or to remove or adjust the seal after it has been placed in locked position. 10 A further object of this invention is to provide a seal which will be not only useful in disclosing any attempt to remove the same from the can but which, after being used to seal the can while en route to the consignee, may be again inserted in the can to retain the cover assembled therewith to insure its return to the shipper. 15

It is another object of the invention to provide a seal consisting of a strip of metal 20 which can be adjusted to the can so as to eliminate slack and, when bent back after being placed in sealing position, will break at the bending point.

An additional object of this invention is 25 to provide a seal of this character which consists of a strip of metal extended across the entire closure and engaged with the flared end of the can in such a manner as to permit this strip being used as a handle.

Another object of the invention is to provide a device of this general character which is simple in construction, inexpensive and efficient.

With the above and other objects in view, 30 which will appear as the description proceeds, the invention resides in the combination and arrangement of parts and in the details of construction hereinafter described and claimed, it being understood that various changes in the precise embodiment of 35 the invention shown can be made without departing from the spirit of the invention.

Figure 1 is a plan view of a portion of a milk can showing the seal applied thereto, 40 the seal being shown in position before the ends thereof are arranged in locked position;

Figure 2 is a like view showing the ends of the seal in locked position;

Figure 3 is a plan view of a modified embodiment of the invention;

Figure 4 is a view of the seal shown in Figure 3 in operative position, the dotted lines indicating the position of the ends of the seal before locked.

Figure 5 is an enlarged sectional view 60 illustrating the tongue and slot connection embodied in the construction illustrated in Figures 3 and 4.

Referring in detail to the drawing, the 65 numeral 5 designates a strip which is formed of a metal which can be bent in one direction but will break if bent in the opposite direction at the same point or points.

Transverse notch 6 is formed in each end 70 portion of the strip and each notch is adapted to receive the opposite longitudinal edge of the strip when in assembled or locked position on the can as illustrated in Figure 2. Extending transversely of each end portion 75 of the strip is a plurality of transverse scores or weakening grooves 7.

The flared end of the milk can designated 80 at 10 is provided with openings 11 at diametrically opposite points for the reception of the ends of the strip 5.

In the application of the device to a milk can, the strip is extended across the can closure and over the handle thereof and its ends are inserted through the openings 11 85 in the neck of the can. These ends are then bent at the weakened points back over the edge of the neck of the can and each notched end is sprung laterally into engagement with the longitudinal edge of the strip as in 90 Figure 2. Should an attempt be made to remove the seal, the same would break at one of the weakened lines.

In the modified form of the invention 95 illustrated in Figure 4 the strip is provided with a longitudinal slot 12 intermediate its ends and one end of which is enlarged as shown at 13. The adjacent end terminates in a key or T-shaped head 14 which is insertable into the large 100 end of slot 12 after the seal has been bent into engagement with the milk can and is pulled to the other end of the slot thus to form a tight loop. The other end of the

strip is the same construction as shown in Figures 1 and 2. With this arrangement all slack in the strip may be readily taken up.

What is claimed is:—

- 5 1. The combination with a milk can having opposed openings and a closure insertable between the openings of a seal comprising a strip of metal inserted through the openings, and over the closure the strip being provided with score lines in one face thereof near its ends, said ends being bent at the score lines to form loops engaging the can, and means at the ends of the strip for engaging intermediate portions of the strip to close the can engaging loops, the strip being adapted to break along any one of the score lines when a loop is opened.
- 10 2. A seal comprising a strip of metal having a notch in one side at one end and a head at its other end, there being a slot in the strip provided with an enlarged end, said strip having transverse score lines near its ends, the strip being bendable along said lines to form loops, the notched portion being movable into engagement with one edge of the strip to close one loop and the head being insertable into and movable within the slot to close and contract the other loop, said strip being adapted to break along one of the score lines when either loop is opened.
- 15 3. A seal comprising an elongated strip having its end portions foldable inwardly, and means upon the ends of the strip for

engagement with intermediate portions of said strip to form closed loops, said strip being formed of a material adapted to break when the strip is partly or entirely straightened at the bends.

4. The combination with a container having opposed openings, of a seal comprising an elongated strip insertable longitudinally through the openings and having its end portions foldable inwardly toward each other, means upon the end portions of the strip for detachably engaging intermediate portions thereof to provide closed loops engaging the apertured portions of the container, said strip being formed of material adapted to break apart when the strip is partly or entirely straightened at the bends.

5. A seal comprising an elongated strip bendable upon itself to form a loop and having a notch in one side for the reception of an opposed portion of the loop, thereby to close the loop, said strip having a portion adapted to be rebent to open the loop, said portion being weakened to insure breaking when rebent.

In testimony that I claim the foregoing as my own, I have hereto affixed my signature in the presence of two witnesses.

WILLIAM KERR EDGAR.
